UNITED STATES PATENT OFFICE.

LOUIS GICLAS, OF WASHINGTON, DISTRICT OF COLUMBIA.

DESIGN FOR AN ADVERTISING SIGN OR SIMILAR ARTICLE.

58,435.

Specification for Design.

Patented July 19, 1921.

Application filed December 29, 1920. Serial No. 433,952. Term of patent 14 years.

To all whom it may concern:

Be it known that I, LOUIS GICLAS, a citizen of the United States, residing at Washington, in the District of Columbia, have invented a new, original, and ornamental Design for an Advertising Sign or Similar Article, of which the following is a specification, reference being had to the accompanying drawings, forming part thereof.

The figure is a plan view of a sign showing my new design.

I claim:

The ornamental design for an advertising sign, or similar article as shown.

LOUIS GICLAS.
